J. W. IVORY,
FINGER NAIL CLEANER.
APPLICATION FILED OCT. 4, 1918.

1,367,974.

Patented Feb. 8, 1921.

UNITED STATES PATENT OFFICE.

JAMES W. IVORY, OF PHILADELPHIA, PENNSYLVANIA.

FINGER-NAIL CLEANER.

1,367,974.

Specification of Letters Patent.

Patented Feb. 8, 1921.

Application filed October 4, 1918. Serial No. 256,891.

To all whom it may concern:

Be it known that I, JAMES W. IVORY, a subject of the King of Great Britain, residing in the city and county of Philadelphia, State of Pennsylvania, have invented a new and useful Finger-Nail Cleaner, of which the following is a specification.

My invention consists of a finger nail cleaner consisting of a thin wedge shaped oval tapering blade having thereon teeth by means of which nails may be effectively cleaned without scratching the nail or irritating the soft tissue or cuticle thereof, the blade being also adapted as a cuticle pusher.

The invention is satisfactorily illustrated in the accompanying drawing, but the important instrumentalities thereof may be varied, and so it is to be understood that the invention is not limited to the specific details shown and described, as long as they are within the spirit or scope of the claim.

Figures 1 and 2 represent perspective view of opposite sides of a finger nail cleaner embodying my invention.

Fig. 3 represents a transverse section thereof on the line 3-3 Fig. 1.

Figs. 4, 5 and 6 represent perspective views of other embodiments of my invention.

Fig. 7 represents a view of the back or underside of the blade shown in Fig. 6.

Similar numerals of reference indicate corresponding parts in the figures.

Referring to the drawings.

1 designates the blade of my finger nail cleaner, and 2 designates the handle thereof. The blade is on the forward terminal of said handle, and has one face convex, oval or rounded and on said face are the teeth 3, while the back 4 of the blade is flat and smooth.

The teeth 3 are pyramidal in form and extend in the direction of the length of the blade, in some cases to the edge of the blade, in others they converge to a point, yet are not deep enough to penetrate the back 4 so that the extreme front edge of the back of the blade and consequently the front edge of the blade is untoothed or unbroken, as shown more particularly in Fig. 2 but said edge is thin and tapering or wedge-like so as to conform to the space between the underside of a finger nail and the adjacent flesh, and the toothed face of the blade conforms to the concavity of the underside of

the nail. If the blade is made of hard metal or material it is left with a dull edge, but if made of an unabrasive material that will not scratch the nail, the teeth are left or made sharp and the V-spaces between them may be supplied with a cleansing powder or lotion of a kind usually employed in manicuring.

The operation is as follows:

After a nail is well brushed with a fine powder or washed with soap and water, the blade is inserted in the space under the nail and manipulated by the handle with a kind of semi-circular movement from side to side. This will thoroughly cleanse the space between the nail and flesh of any dirt or foreign matter lodged in said space or clinging to the underside of the nail, while at the same time, the nail will not only be cleaned and beautified, but it will be strengthened as there will be an extra flow of blood to the parts with which the blade is contiguous due to the massage that is occasioned by the blade.

In the case of a cuticle pusher, by the use of the blade, the scarf skin may be gently pushed back by the same. The blade may be integral with the handle, and the latter may be somewhat flat or circular as shown in several figures of the drawing.

In Fig. 4, a shoulder 5 is formed at the place of junction of the blade with the handle.

In Fig. 5 the blade is shown separate from the handle, and its shank is held thereon by the jaws 6 which extend from the handle.

In Fig. 6 the handle has thereon the knurl 7 for firmly grasping the same during manipulation.

Having thus described my invention what I claim as new and desire to secure by Letters Patent is:

A nail cleaner consisting of a thin substantially flat blade and a handle therefor, one end of the blade having on one side a rounded face, and on the other side a flat face, and pyramidal teeth on said rounded face, the edge of said end being curved and untoothed on both faces.

JAMES W. IVORY.
